Alfred Goldman, 1535 Undercliff Ave., New York, N.Y.,
and Reginald Spooner, 1991 Sedgewick Ave., New
York, N.Y.

Filed May 6, 1965, Ser. No. 85,146

Term of patent 14 years

(Cl. D52—6)

Fig. 1

FIGURE 1 is a plan view of a drawing guide showing our new design; and

FIGURE 2 is an end elevational view thereof.

The bottom of the drawing guide is plain in appearance.

The dominant features of the design reside in the portions shown in solid lines.

We claim:

The ornamental design for a drawing guide, substantially as shown and described.
